(57) **CLAIM**

The ornamental design for display screens with user interface, as shown and described.

DESCRIPTION

FIG. 1 is a front perspective view of display screens with user interface in “active” mode, showing the new design; FIG. 2 is a perspective view as shown in FIG. 1, in “standby” mode;

FIG. 3 is a perspective view as shown in FIG. 1 illustrating touch screen for “active” mode;

FIG. 4 is a front elevation view thereof in “active” mode; FIG. 5 is a front elevation view thereof in “standby” mode; and,

FIG. 6 is a side plan view thereof, the opposite side plan view, the top plan view, and the bottom plan view being identical to FIG. 6.

The broken lines and alpha-numeric display in FIG. 3 illustrate environmental structure associated with the display screens with user interface, the environmental structure of

(Continued)

the broken lines being that of a human hand, forming no part of the claimed design. The new design is of a thermostat for locating in a room.
